UNITED STATES PATENT OFFICE

WALTER EVERETT MOLINS, OF DEPTFORD, LONDON, ENGLAND

MOISTUREPROOF ENVELOPE OR WRAPPER

Application filed April 5, 1928, Serial No. 267,774, and in Great Britain April 29, 1927.

This invention is for improvements in or relating to moisture-proof envelopes and relates more particularly to a moisture-proof wrapper particularly for use in enveloping articles, such as cigarettes, easily affected by climatic conditions.

It has been proposed hitherto to envelop the articles in an outer wrapper which is impregnated with wax, but such wrappers have the distinct disadvantage that they are easily soiled by dust and dirt, besides being very unpleasant to handle.

Further, in wrappers of this character, the overlapping edges are sealed by melting the wax and allowing the same to cool, which method does not provide a very secure joint and consequently the moisture-proof properties of the envelope are very easily destroyed.

In view of the disadvantages enumerated above, impregnated wax wrappers are not used to any considerable extent commercially, and yet it is an undoubted fact that a wax covered wrapper is an extremely suitable moisture-proof material for covering articles such as cigarettes where the contents have to be protected against climatic conditions which are liable to interfere seriously with the quality or conditions of the cigarettes.

It is an object of the present invention to provide a moisture-proof wrapper particularly for use in enveloping articles such as cigarettes easily affected by climatic conditions, which will permit the overlapping edges of the wrapper to be securely sealed together by means of gum or a like adhesive, and yet maintain the outer surface of the wrapper smooth so that it does not pick up dirt or dust and yet possess a moisture-proof inner surface which protects the wrapped articles against varying climatic conditions.

The present invention consists of a moisture-proof envelope wherein the whole of the inner surface is provided with a coating of wax applied to one side of a wrapper from which the envelope is formed in such a manner as to leave those portions of the waxed side of the wrapper which have to be secured by adhesive to portions of the unwaxed side of the wrapper, free of wax.

Again, the present invention consists of a moisture-proof envelope as set forth in the preceding paragraph, wherein overlapping folds of the un-waxed side of the wrapper are provided with a covering of wax for the purpose hereinafter set forth.

The invention is more particularly described with reference to the accompanying drawings, in which:—

Fig. 1 shows a side elevation of a box covered with a wrapper made according to this invention.

Fig. 2 shows a wrapper blank of the kind described in specification No. 259,165 but coated with wax in the manner herein described.

Fig. 3 shows a blank of the kind described in specification No. 21,780 of 1927, similarly coated.

Fig. 4 shows the reverse side of the blank illustrated in Fig. 1, when the same has wax applied upon those portions thereof which comprise the overlapping sections of the side tucks and end folds.

Referring to the drawings, the method of carrying the invention into effect consists in imprinting upon one surface *a* of a wrapper of transparent paper, a coating of wax which extends over the entire length of the same, leaving an unwaxed section 1 at one end thereof.

Further, one half of the waxed wrapper is provided with a coating of wax which does not extend across the full width of the wrapper, thus leaving a margin 2 on either side thereof for a purpose hereinafter set forth.

The wrapper so coated may be employed to envelop a rectangular packet of cigarettes in a U-shaped block ended envelope so that the unwaxed narrow margin 2 formed at each side of the wrapper is arranged to overlie a portion of the unwaxed side of the wrapper and be secured thereto by any suitable adhesive as shown at Fig. 1. The end of the block ended envelope is folded inwardly so as to form two side folds and the two broad end flaps are folded so that the flap provided on its inner surface with the unwaxed section 1 is arranged so as to constitute the last folded flap of the wrapper, and this flap is folded and secured by any suitable adhesive to the un-

100

waxed surface of the other broad end flap or the adjacent broad face of the wrapper.

Thus it will be seen that a transparent covering is provided for a packet of cigarettes having an inner coating of wax and that the only possible parts of the covering at which the same is not entirely moisture-proof occurs between the interstices formed between the overlapping folds of the wrapper at the open end thereof, and at the side tucks formed near the block end of the wrapper.

If necessary, the wrapper may be completely sealed by applying to the unwaxed side *b* (Fig. 3) of the wrapper three sections of wax 3, 4 and 5 along each side edge of the wrapper as shown in Fig. 3 so that the said sections of wax occur substantially at each end and at the central section of the wrapper. It will be found that by applying wax in this manner the interstices between the overlapping folds of the wrapper will be filled with wax which, as the enveloped packet passes through a heater, melts and thereafter cools to form a moisture-proof seal between the side folds and end tucks of the wrapper, thus rendering the envelope entirely moisture-proof and protecting the enveloped articles against variable climatic conditions.

30 It will be observed by reference to the drawings that a narrow margin 6 is shown at either end of the blanks. This margin is one half of a narrow uncoated strip left between each blank when the blanks are printed 35 from a web, fed from a reel. The narrow strip is left uncoated between each blank so that the cutting knife may operate without clogging.

By enveloping articles in a transparent 40 wrapper treated in the manner hereinbefore set forth it is possible to eliminate the provision of a more expensive moisture-proof wrapping and in this way considerably reduce the cost of the article, besides materially increasing the moisture-proof properties of the 45 wrapper.

What I claim as my invention and desire to secure by Letters Patent is:—

1. A moisture-proof blank for completely 50 encasing an article, said blank having portions designed to overlap other portions of the blank when the latter is applied as a wrapper to an article, such blank having that portion only of the inner surface thereof 55 which does not overlap the outer surface when finally applied coated with waterproofing material.

2. A moisture-proof blank for completely 60 encasing an article, said blank having portions designed to overlap other portions of the blank when the latter is applied as a wrapper to an article, such blank having that portion only of the inner surface thereof 65 which does not overlap the outer surface when finally applied coated with waterproofing

material, and having waterproofing material on such portions only of the outer surface thereof as to effect a seal in the interstices of the fold.

3. A blank for forming a moisture-proof envelope for completely encasing an article, portions of the blank being designed to overlap other portions of the blank when the latter is applied as a wrapper to the article to facilitate sealing of the envelope with adhesive, said blank having a design of wax imprinted on the inner surface thereof so as to cover all remaining portions of the blank.

In testimony whereof I hereunto affix my signature.

WALTER EVERETT MOLINS.
